VALVE

Charles F. Fernald, Weston, Mass., assignor to
Barnes & Jones, Incorporated, Boston, Mass.,
a corporation of Massachusetts

Application November 10, 1931
Serial No. 574,109

12 Claims. (Cl. 236—58)

This invention relates to automatic valves for controlling fluids under pressure and pertains more particularly to improvements in the construction of thermostatic valves adapted to regulate the flow of fluids subject to temperature and pressure variations, for example, outlet valves for steam radiators. In the Patent No. 1,738,248 granted to Jones on December 3, 1929, there is disclosed one desirable arrangement whereby the valve actuating element, for example, a metallic bellows or the like, is removably supported with some freedom for lateral swing in any direction in order to enable the valve to seat accurately. While the device disclosed in the aforesaid patent is eminently well adapted to perform its intended function, I find that when it is exposed to sudden shocks or blows, as often happens during transportation or installation, the actuating element is sometimes released from its supporting means so that the valve will not operate properly without resetting; furthermore the device disclosed in said patent is somewhat more expensive to manufacture than is desirable.

The present invention which is an improvement over that disclosed in the patent above referred to, retains all of the operative advantages of the prior construction, but in addition provides a support for the actuating element and valve which effectively prevents separation of the parts by sudden shock or blows (although readily allowing intentional separation) while at the same time the construction is such as to permit its manufacture at a substantially lower cost than the device of the aforesaid patent.

In the accompanying drawing wherein certain desirable embodiments of the invention are disclosed by way of example,

Fig. 1 is a vertical section through an outlet valve embodying the present invention;

Fig. 2 is a vertical section through the cap or cover of the valve device, with the valve supporting and actuating elements removed;

Fig. 3 is a view showing the inside of the valve cap or cover with the supporting element appertaining thereto in its operative position;

Fig. 4 is a plan view of a preferred form of supporting element;

Fig. 5 is a side elevation of the supporting element of Fig. 4; and

Figs. 6 and 7 are plan views of supporting elements of slightly different construction.

Referring to the drawing the numeral 6 designates the usual valve casing which may be of cast iron or other suitable material having the inlet connection 7, the outlet connection 8 and the

removable fluid tight cover 9,—the latter being here shown as having screw threaded engagement with the body of the casing. This casing with its cover provides the chamber 11 which communicates with the inlet 7 and, through a valve port 12, with the outlet 8. This chamber houses an automatic actuating or controlling element consisting for example of one or more expansible metal cells 14 carrying a valve 15, properly shaped to cooperate with the valve seat 16 surrounding the port 12. As here shown and in accordance with one desirable construction, the cells 14 of the actuator are substantially circular and are attached to a stem which projects below the lower cell 14 and to which the valve 15 is secured. The upper end of the stem projects above the upper cell 14 and carries a knob 17 here shown as a ball or bulbous member preferably of substantially spherical curvature, the center of this knob being disposed substantially on the axis of the stem of the actuating element.

In accordance with a preferred construction, the cover is provided with a central recess 18 having the surface 18a against which the knob or ball 17 is normally pressed as hereinafter described. This recess 18 is preferably coaxial with the valve seat 16 and its lateral wall is furnished with an annular groove 19 (Fig. 3) which may be formed in any desired manner either in the operation of casting the cap or by machining the cap, as may be preferred. This groove 19 furnishes a seat for a supporting element which, in its preferred form, is illustrated in Figs. 4 and 5. This supporting device may conveniently be made by properly bending a piece of resilient wire, preferably bronze, or other material which is not substantially affected by the fluids which enter the chamber 11. As shown in Fig. 4, the wire or other material forming this supporting member 20 is bent to form a plurality of lobes 21 (preferably arcuate) disposed substantially in the same plane and which are adapted to seat within the groove 19. Preferably this supporting member is provided with a gap at the point 20a to permit it to be contracted slightly in snapping it into the groove, although, even if the ring-like portion of this supporting member were continuous it would be possible to contract it by reason of its lobal shape. The arcuate portions 21 of this device are separated by projecting bends or loops 22 which extend downwardly, as here shown, from the plane of the parts 21 and which constitute claws for supporting the ball 17. Those claws preferably converge toward their free ends (or if desired may be of curved contour) so that their

tips are closer together than their root portions where they join the parts 21.

This supporting member 20 is assembled with the cover by snapping the parts 21 into the groove 19 so that the claws 22 depend into the chamber 11. Since these claws are resilient, it is possible to push the ball 17 up into the space between them and as will be noted from Fig. 1, the tips of the claws are so arranged as to engage the ball 17 at points well below the horizontal plane defining the center of the ball. As thus arranged, the resilient claws 21 exert a constant upward pressure on the ball 17 such as to force the latter into firm engagement with the surface 18^a of the cover, having in this respect the same function as the spring ring of the aforesaid patent to Jones. However, it is to be noted that the present construction is simpler than that of said patent, since in the patented device it is necessary to provide an independent retainer member for the spring ring which adds substantially to the cost of production.

Not only do the claws 22 reach downwardly to a point below the horizontal plane of the center of the ball 17 so as normally to keep the ball in contact with the cover, thus holding the valve at a definite distance from its seat, but preferably they reach down to a point so far below said plane that even if the actuator device as a whole be accidentally displaced downward (as by a sudden shock) until stopped by engagement of the valve 15 with its seat, the tips of the claws 22 will still contact with the ball 17 at a point below the plane passing through the center of the ball, so that even if thus displaced to the maximum possible extent, the ball and actuator will immediately be restored to normal position by the reactive force of the resilient claws. Thus the improved construction obviates any danger of accidental displacement of the valve parts during transportation or installation, although when the cover is removed the ball with the actuator and valve may readily be disengaged from the claws 22 by the exertion of downward pull.

While the arrangement shown in Figs. 4 and 5 is desirable,—such arrangement involving the employment of three equally spaced claws 22, I contemplate the employment of an arrangement such as shown in Fig. 6 wherein four claws 22^a with interposed arcuate members 21^a are provided, or one like that of Fig. 7 wherein two claws 22^b separated by the arcuate portions 21^b are used, respectively. Alternately, the several claws may be independent, more or less resilient, claw members securely set into the material of the cover, and properly shaped to hold the ball 17 in the same way as the claws already described.

I claim:

1. A valve structure comprising a casing having a valve seat, a removable cover having fluid tight engagement with the casing, an actuating element within the casing, a valve secured to the actuating element and cooperable with said seat, a knob attached to said element, and a plurality of resilient claws adapted to receive the knob between them and resiliently to hold the knob in engagement with the inner surface of the cover member thereby removably to retain the parts in adjusted relationship while permitting the valve to center itself upon its seat.

2. A valve structure comprising a casing including a removable cover having fluid tight engagement with the body of the casing, said casing having a valve seat within it, an actuating element within the casing, a valve secured to the lower end of the actuating element, a knob secured to the upper end of the actuating element, said knob having an under surface which slopes upwardly and outwardly, to a point of maximum diameter,

actuating element and cooperable with said seat, a knob secured to said element, and a plurality of downwardly convergent resilient claws adapted to receive the knob between them and to hold the knob in contact with the inner surface of the cover member.

3. A valve structure comprising a casing including a removable cover having fluid tight engagement with the body of the casing, said casing having a valve seat within it, an actuating element within the casing, a valve secured to the actuating element and cooperable with said seat, a knob secured to said element, said knob being of spherical curvature, and a plurality of resilient claws depending from the inner surface of the cover, the tips of said claws engaging the knob at points below the plane of its maximum horizontal diameter.

4. A valve structure comprising a casing including a removable cover having fluid tight engagement with the body of the casing, said casing having a valve seat within it, an actuating element within the casing, a valve secured to the actuating element and cooperable with said seat, a knob secured to said element, said knob being of substantially spherical curvature, and a plurality of downwardly convergent claws carried by the cover, said claws being so spaced as removably to receive and resiliently to hold the knob between them, the tips of the claws engaging the knob below the plane of its maximum diameter.

5. A valve structure comprising a casing including a removable fluid tight cover, the casing having a valve seat within it, an actuating element within the casing, a valve secured to the lower end of the actuating element, a knob attached to the upper end of the actuating element, and supporting means comprising a resilient member having arcuate portions engaging the cover and spaced claw members engageable with the knob for removably supporting the latter with the attached actuating element and valve.

6. A valve structure comprising a casing including a removable fluid tight cover, the casing having a valve seat within it, an actuating element within the casing, a valve secured to the lower end of the actuating element, a knob attached to the upper end of the actuating element, and supporting means comprising an elongate member bent to provide concentric lobal portions adapted for anchorage to the cover member, and claw portions between said lobal portions, said claw portions being adapted releasably to engage the knob for supporting the latter with the actuator and valve.

7. A valve structure comprising a casing including a removable fluid tight cover, the casing having a valve seat within it, an actuating element within the casing, a valve secured to the lower end of the actuating element, a ball attached to the upper end of the actuator element, the cover having an annular groove concentric with the axis of the valve seat, and a supporting device consisting of a resilient snap ring adapted to seat in said groove and having depending claws for embracing and removably supporting the ball with its attached actuator and valve.

8. A valve structure comprising a casing including a removable fluid tight cover, the casing having a valve seat within it, an actuating element within the casing, a valve secured to the lower end of the actuating element, a knob secured to the upper end of the actuating element, said knob having an under surface which slopes upwardly and outwardly, to a point of maximum diameter,

- from the point of attachment of the knob to the actuating element, a device carried by the cover for supporting the knob with its actuator and valve, said supporting device comprising means 5 constituting a universal bearing in which the knob is free to rock in all directions whereby the valve may center itself on its seat, said bearing means comprising relatively yieldable resilient portions engaging the sloping under surface of the 10 knob in a plane spaced below the plane of maximum diameter of the knob a distance substantially greater than that which separates the valve and its seat when the actuator is exposed to normal atmospheric conditions, the resilient means 15 being so constructed and arranged as to continue to engage and exert pressure against the sloping under surface of the knob below the plane of its maximum diameter even if the actuator and valve are displaced downwardly to maximum possible 20 extent as limited by engagement of the valve with its seat, the slope of the knob surface at the contact point being such as to develop a vertical component of the resilient pressure sufficient to restore the actuator and valve to normal position. 25 9. A valve structure comprising a casing including a removable fluid tight cover, the casing having a valve seat within it, actuating means within the casing, a valve secured to the actuating means for cooperation with the valve seat, a ball attached 30 to the actuating means, the cover having a central recess in which the upper part of the ball is disposed, the side wall of the recess having a circumferential groove therein in a plane above the center of the ball, a supporting device seated in 35 said recess and having downwardly extending resilient elements engaging the ball in a plane below its center and forming a bearing in which the ball may rock freely in all directions, said resilient elements being operative to engage an upward restoring force to return the ball to normal position 40 in the recess if the ball is accidentally displaced downwardly therefrom.
10. A valve structure comprising a casing having a valve seat, a removable cover having fluid tight engagement with the casing, an actuating element within the casing, a valve secured to the actuating element and cooperable with the seat, a ball secured to the actuating element, and means carried by the cover constituting a supporting bearing in which the ball is free to swing whereby the valve is enabled to center itself with reference to its seat, said supporting bearing comprising relatively yieldable resilient portions engaging the ball in a plane spaced below the center of the latter by a distance substantially greater than the distance which separates the valve and its seat when the actuator is exposed to normal atmospheric conditions, the resilient portions of the bearing being so constructed and arranged as to continue to engage and exert pressure against the under surface of the ball below the plane of the center of the latter even if the actuator and valve are displaced downwardly to the maximum possible extent as limited by engagement of the valve with its seat, the slope of the under surface of the ball at the contact point being such as to develop a vertical component of the resilient pressure sufficient to restore the actuator and valve to normal position. 95
11. A supporting device for use in valves of the class described, said device comprising a resilient member having spaced lobal portions disposed substantially in a plane and interposed claw members projecting from said plane, said claw members converging toward their tips. 100
12. A supporting device for use in valves of the class described, said device comprising an elongate piece of resilient material bent to form a split snap ring comprising spaced arcuate portions and interposed loops forming claws projecting to one side of the plane of said arcuate portions and having their tips disposed closer together than 110 their roots. 115
